ABSTRACT OF THE DISCLOSURE

A process for producing hydrogen from an excess refinery stream or mixture of refinery streams by hydrocracking, steam reforming a vaporous fraction from the hydrocracking step, contacting the effluent from the reforming step admixed with additional steam with a water gas shift catalyst, recycling a portion of the hydrogen separated from the shift reaction to the hydrocracking step, and recovering the remainder of the hydrogen as product.

This invention relates to a process for producing hydrogen from excess refinery streams ranging from C₆ to heavy oils.

In most petroleum refineries a complete balance of operations is rarely achieved. Usually, there is an excess of materials such as naphtha, distillates, gas oils, residual oils, and the like, and there is almost always a deficiency of hydrogen for use in hydrotreating, hydrogenation, hydrocracking, and similar operations.

This invention is concerned with a process for converting excess liquid petroleum streams to hydrogen.

Accordingly, it is an object of the invention to provide a process for converting liquid hydrocarbons to hydrogen. Another object is to provide a simple and efficient process for converting liquid hydrocarbons into H₂ and CO₂ with recovery of heavy aromatic oils from the process. Other objects of the invention will become apparent to one skilled in the art upon consideration of the accompanying disclosure.

In accordance with the invention, a liquid hydrocarbon feed comprising an excess refinery stream or a mixture of refinery streams ranging from C₆ to heavy oils is hydrocracked in admixing with hydrogen under severe hydrocracking conditions; the hydrocracking effluent is cooled so as to condense C₆ and heavier hydrocarbons therein with separate recovery of the vaporous fraction and the liquid fraction; the vaporous fraction is admixed with steam and passed to a steam reforming step in contact with a reforming catalyst to produce principally H₂, CO, and CO₂; the effluent from the steam reforming step is admixed with additional steam as required for reaction and/or cooling, and passed to a water gas shift step for conversion of the CO to CO₂ in contact with a shift reaction catalyst to produce additional H₂; and the gaseous effluent from the shift reaction is separated into an H₂ stream and a CO₂ stream, a portion of the H₂ being recycled to the hydrocracking step and the remaining portion being recovered as product H₂. The effluent from the hydrocracking step is partially condensed in indirect heat exchange with water to convert the water to steam, which is then passed to the steam reforming step and to the water gas shift reaction. The C₆ and heavier hydrocarbons comprising the condensate from the cooling step is passed to a separation zone for recovery of a heavy aromatic oil as a product of the process and a lighter fraction which is recycled to the hydrocracking step. When catalytic hydrocracking is used, essentially no heavy aromatic oil is made, and the total liquid product is recycled to the hydrocracking zone.

The liquid oil feed is hydrocracked under severe cracking conditions, either pyrolytically or catalytically, such

2

that only about 5 to 12 percent of the feedstock is yielded as heavy aromatic hydrocarbons. Operating conditions in the hydrocracking zone or step include a ratio of hydrogen to feedstock in the range of 1,000 to 15,000 cu. ft./bbl., a pressure in the range of 250-1000 p.s.i.g., a temperature in the range of 750-1350° F., and a liquid hourly space velocity in the range of 0.1 to 10 (catalytic) or a contact time of 0.1 to 10 minutes (pyrolytic). It is preferred to utilize a catalyst but pyrolytic hydrocracking is feasible.

Any hydrocracking catalysts having both a hydrogenation component and a cracking component may be utilized. Preferred catalysts include the metals, oxides and/or sulfides of nickel, molybdenum, platinum, palladium, ruthenium, tungsten, and/or cobalt deposited on alumina, silica-alumina, silica-zirconia, or silica-magnesia support.

Conditions in the steam reforming zone include a steam to dry gas mol ratio in the range of 1:1 to 10:1, a pressure in the range of 250-1000 p.s.i.g., a temperature in the range of 1250-1600° F., and a dry gas hourly space velocity in the range of 500 to 10,000. The preferred catalyst is nickel on alundum (aluminum oxide) but any of the steam reforming catalysts known to the industry may be utilized.

In the water gas shift reaction, conditions include a steam to dry gas mol ratio in the range of 0.5:1 to 3:1, a pressure in the range of 300-500 p.s.i.g., a temperature in the range of 450-850° F., a dry gas hourly space velocity in the range of 500 to 5,000, and, preferably, an iron oxide-chromium oxide catalyst. Other water gas shift reaction catalysts known to the industry, such as zinc-copper chromite, may be utilized.

Separation of H₂ and CO₂ from the effluent from the water gas shift reaction is effected, for example, by absorption of the CO₂ in ethanolamine in conventional manner. Any manner of effecting this separation is within the scope of the invention.

The C₆ and heavier oil fraction downstream of the condensation step is either separated by fractional distillation or any other conventional means into a heavy aromatic oil and a lighter fraction which is recycled to the hydrocracking step (pyrolytic hydrocracking) or is recycled without such a separation step (catalytic hydrocracking). The heavy aromatic oil is a marketable product of the operation, for example, for carbon black manufacture.

A more complete understanding of the invention may be had by reference to the accompanying schematic drawing, which is a flow or arrangement of apparatus suitable for performing the invention.

Referring to the drawing, a suitable liquid oil feed in line 10 is fed to hydrocracking unit 12 in admixture with hydrogen from line 14 and the liquid oil fraction from line 16 obtained as hereinafter disclosed. The hydrocracked effluent is passed via line 18 thru indirect heat exchanger 20 and cooled therein by heat exchange with water introduced thru line 22 which converts at least the major portion of the water to steam. The heat exchange in exchanger 20 is controlled so as to condense the C₆ and heavier hydrocarbons and leave most of the C₅ and lighter hydrocarbons in vapor form. The effluent from exchanger 20 passes thru line 24 into knock-out drum 26, the liquid oil being withdrawn from the bottom of the drum thru line 28 and the overhead vapor being passed thru line 30 to steam reforming zone 32 in admixture with steam from line 34 which connects with line 22.

The effluent from steam reforming zone 32 consisting essentially of H₂, CO, and CO₂, along with steam, is passed via line 36 to water shift reaction zone 38 in admixture with added steam from line 40. The water shift reaction converts CO to CO₂ with the formation of additional hydrogen, the effluent from this reaction being passed via line 42 to separation or absorption zone 44

where it is contacted with ethanolamine from line 45. The ethanolamine, containing CO_2 , is withdrawn from this zone thru line 46 and passed to CO_2 recovery means (not shown) to condition the ethanolamine for reuse in the process. The CO_2 is recovered as a product of the process. The hydrogen remaining in vapor form after contacting with the ethanolamine is recovered thru line 48, a minor portion being recycled thru line 14 to the hydrocracking operation in zone 12 and the major portion being recovered as hydrogen for use in refinery processes or for any other suitable use.

The liquid C_6 to heavy aromatic oil fraction recovered from knock-out drum 26 thru line 28 is passed to separation zone 50 in which the oil stream is fractionated into a heavy aromatic oil fraction and a lighter oil fraction, the former being recovered as a product of the process thru line 52 and the latter being passed thru lines 16 and 10 to the hydrocracking step, or is recycled directly to the hydrocracking step via line 51.

The following example is illustrative of the process 20 of the invention but is not to be construed as unnecessarily limiting the invention:

EXAMPLE

A kerosene distillate boiling in the range of 350 to 25 520° F. and having a gravity of 40° API is diluted with 8000 cubic feet of hydrogen per barrel, and pyrolytically hydrocracked at 500 p.s.i.g. and 1300° F., with a contact time of 1 minute. About 10 weight percent heavy aromatic oil is formed. Product gases amount to 8700 cubic 30 feet per barrel of kerosene and have the following approximate composition:

	Mol percent
Hydrogen	40
Methane	40
Ethane	17
C_3+	3

These product gases are then reacted with steam at a mol ratio of steam to dry gas of 2:1 and a dry gas hourly space velocity of 1500 over a nickel-alumundum catalyst at about 500 p.s.i.g. and 1500° F. to convert the hydrocarbons to hydrogen and the oxides of carbon. This mixture is further reacted with additional steam over an iron oxide-chromium oxide shift catalyst using a steam to dry gas ratio of 0.6:1, a pressure of 400 p.s.i.g., a temperature of 800° F., and a dry gas hourly space rate of 1500 to convert the carbon monoxide to carbon dioxide with formation of additional H_2 , and the carbon dioxide in the resulting stream is absorbed in ethanolamine. This operation produces 31,000 cubic feet of hydrogen per barrel of kerosene of which 8000 cubic feet are recycled. Thus, the net hydrogen production is 23,000 cubic feet per barrel of kerosene.

The foregoing example clearly demonstrates the effectiveness of the process in producing large amounts of hydrogen per barrel of feed, the net hydrogen production being 23,000 cu. ft./bbl. of kerosene distillate. Other excess refinery streams of liquid oils, alone or in admixture, are amenable to hydrogen production in accordance with the invention.

Certain modifications of the invention will become apparent to those skilled in the art and the illustrative details disclosed are not to be construed as imposing unnecessary limitations on the invention.

I claim:

1. A process for producing H_2 from a feed comprising available refinery oils ranging from C_6 to heavy oils, which comprises the steps of:

- (a) hydrocracking a stream of said oils in admixture with H_2 under severe conditions to form principally C_5 and lighter hydrocarbons;
- (b) cooling the cracked effluent from step (a) to condense C_6 and heavier hydrocarbons including heavy aromatic oils and leave C_5 and lighter hydrocarbons in vapor form;

- (c) catalytically reforming the vapor effluent from step (b) in the presence of steam to convert same principally to H_2 , CO , and CO_2 ;
- (d) contacting the effluent from step (c) in admixture with steam with a water gas shift reaction catalyst to increase the production of H_2 ;
- (e) selectively removing CO_2 from the effluent from step (d) thereby leaving the H_2 in the vapor form;
- (f) recycling a portion of the H_2 of step (e) to step (a);
- (g) recovering the remaining portion of H_2 from step (e) as product,
- (h) separating the C_6 and heavier fraction of step (b) into a heavy aromatic oil fraction as a product and a lighter fraction, and
- (i) recycling the lighter fraction of step (h) to step (a).

2. The process of claim 1 wherein step (a) is effected pyrolytically and only about 5 to 12 weight percent of the feed is yielded as heavy aromatics.

3. The process of claim 1 wherein step (b) is effected by indirect heat exchange with water to form steam and resulting steam is used as steam in steps (c) and (d).

4. A process for producing hydrogen from a feed comprising essentially a kerosene distillate boiling in the range of about 350° to 520° F., which comprises the steps of:

- (a) hydrocracking said feed in admixture with H_2 under severe conditions of a ratio of H_2 to feed in the range of 1000 to 15,000 cubic feet per barrel, a pressure in the range of 250 to 1000 p.s.i.g., a temperature in the range of 75 to 1350° F., and a contact time in the range of 0.1 to 10 minutes in the absence of a catalyst, to form principally C_5 and lighter hydrocarbons;
- (b) cooling the cracked effluent from step (a) to condense C_6 and heavier hydrocarbons including heavy aromatic oils and leave C_5 and lighter hydrocarbons in vapor form;
- (c) passing the vapor effluent from step (b) to a catalytic steam reforming step including a nickel-alumundum catalyst, a steam to dry gas mol ratio in the range of 1:1 to 10:1, a pressure in the range of 250 to 1000 p.s.i.g., a temperature in the range of 1250 to 1600° F., and a dry gas hourly space velocity in the range of 500 to 10,000, to convert said vapor effluent principally to H_2 , CO , and CO_2 .
- (d) passing the effluent from step (c) in admixture with steam to a water gas shift step with a steam to total dry gas mol ratio in the range of 0.5:1 to 3:1, a pressure in the range of 300 to 500 p.s.i.g., a temperature in the range of 450 to 850° F., a dry gas hourly space velocity in the range of 500 to 5000, and an iron oxide-chromium oxide catalyst, to increase the production of hydrogen;
- (e) passing the effluent from step (d) to a separation absorption step where it is contacted with ethanolamine to remove CO_2 and to leave H_2 in the vapor form;
- (f) recycling a portion of the H_2 of (e) to step (a); and
- (g) recovering a remaining portion of H_2 from step (e) as product.

5. The process of claim 4 wherein step (a) is effected pyrolytically and only about 5 to 10 weight percent of the feed is yielded as heavy aromatics.

6. The process of claim 4 including the step of:

- (h) recycling the condensate of step (b) to step (a).

7. The process of claim 4 including the steps of:

- (h) separating the C_6 and heavier fraction of step (b) into a heavy aromatic oil fraction as a product and a lighter fraction; and
- (i) recycling the lighter fraction of step (h) to step (a).

8. A process for producing H_2 from a feed comprising available refinery oils ranging from C_6 to heavy oils,

75 which comprises the steps of:

- (a) hydrocracking a stream of said oils in admixture with H₂ under severe conditions to form principally C₅ and lighter hydrocarbons, said severe conditions including a ratio of H₂ to feed in the range of 1000 to 15,000 cu. ft./bbl., a pressure in the range of 250 to 1,000 p.s.i.g., a temperature in the range of 750 to 1350° F., and a contact time in the range of 0.1 to 10 min. in the absence of a catalyst;
- (b) cooling the cracked effluent from step (a) to condense C₆ and heavier hydrocarbons including heavy aromatic oils and leave C₅ and lighter hydrocarbons in vapor form;
- (c) catalytically reforming the vapor effluent from step (b) to convert same principally to H₂, CO, and CO₂, using a nickel-alundum catalyst, a steam to dry gas mol ratio in the range of 1:1 to 10:1, a pressure in the range of 250 to 1000 p.s.i.g., a temperature in the range of 1250 to 1600° F., and a dry gas hourly space velocity in the range of 500 to 10,000;
- (d) contacting the effluent from step (c) in admixture with steam in a steam to total dry gas mol ratio in the range of 0.5:1 to 3:1, at a pressure in the range of 300 to 500 p.s.i.g., a temperature in the range of 450 to 850° F., a dry gas hourly space velocity in the range of 500 to 5000, with a water gas shift reaction catalyst comprising an iron oxide-chromium oxide catalyst, to increase the production of H₂;
- (e) selectively removing CO₂ from the effluent from step (d) thereby leaving the H₂ in the vapor form;
- (f) recycling a portion of the H₂ of step (e) to step (a); and

- 5 (g) recovering the remaining portion of H₂ from step (e) as product.
